UNITED STATES PATENT OFFICE

WILLIAM DEMUTH, OF NEW YORK, N. Y.

DESIGN FOR PIPE-STEM.

Specification forming part of Design No. **11,278**, dated July 1, 1879; application filed May 29, 1879.
[Term of patent 7 years.]

To all whom it may concern:

Be it known that I, WILLIAM DEMUTH, of the city, county, and State of New York, have originated a new Pattern for Pipe-Stems, of which the following is a full, clear, and exact description, reference being had to the accompanying drawings, making part of this specification.

This design is represented in the accompanying drawings, in which—

Figure 1 represents a stem, in perspective view, containing my design. Fig. 2 is a rear view thereof.

Similar letters indicate corresponding parts.

This design consists in a pipe-stem having a prism containing dots on its exposed sides or faces, as will more fully hereinafter appear.

In the drawings, the letter A designates a stem embodying a dotted prism, B, also a set of moldings, C, above the prism, and a set of moldings, D, below the same. The upper molding, C, consists of a bead joining with the prism, and surmounted by a short cylindrical portion terminating in a polygonal col-

lar, from which extends the curved stem. The lower molding has the general form of the base of a pillar.

The dots of the prism B are on its exposed sides, and each of such sides contains a certain definite number thereof, the whole being intended to represent dice or dominos, while the moldings C D set off or unite the prism with the plain portions of the stem A.

By the features set forth I produce a stem having a novel and distinguishing appearance.

What I claim as new, and desire to secure by Letters Patent, is—

The design for a pipe-stem having a prism provided with dots on its exposed sides or faces, substantially as shown and described.

In testimony that I claim the foregoing I have hereunto set my hand and seal this 23d day of May, 1879.

WM. DEMUTH. [L. s.]
